Continuation-in-part of design application Ser. No. 12,747, June 15, 1968, now Patent No. 214,280, dated May 27, 1969. This application Feb. 5, 1969, Ser. No. 15,653.

Term of patent 14 years

Int. Cl. D7—02

U.S. Cl. D44—1

FIG. 1

FIG. 2

FIG. 1 is a top plan view of a cookie baking sheet, showing my new design.

FIG. 2 is a cross-section on line 2—2 of FIG. 1.

The characteristic feature of this design resides in the elongated slot in the longitudinal center of the sheet.

This application is a continuation in part of my application Ser. No. D. 12,747 filed June 15, 1968, now Pat. No. D. 214,280.

I claim:

The ornamental design for a cookie baking sheet, as shown and described.
